SAMPLE AND SAMPLE CONTAINER

Filed Feb. 23, 1927

UNITED STATES PATENT OFFICE.

EDWIN MARSHALL KINSEY, OF RIVERSIDE, NEW JERSEY.

SAMPLE AND SAMPLE CONTAINER.

Application filed February 23, 1927. Serial No. 170,282.

This invention relates to improvements in samples and means for carrying the same.

The primary object of this invention is the provision of an improved sample carrying kit, or box, adapted to be used for the compact filing and efficient arrangement of sample colors, or the like.

A further object of this invention is the provision of an improved sample carrying receptacle embodying improved means for compactly carrying a large number of samples of flexible material, in an efficient and compact relation, so that the same may be readily detached or relatively rearranged in a manner which will permit of the individual inspection of the same.

A further object of this invention is the provision of an improved sample and sample carrying case for the same, adapted to be more particularly used by hosiery manufacturers and the like, the same including a filing receptacle adapted to frictionally retain therein a large number of samples of flexible material in such an exposed relation that the same may be individually inspected, or individually removed, without a disarrangement of adjacent or other samples.

Other objects and advantages of this invention will be apparent during the course of the following detailed description.

In the accompanying drawing, forming a part of this specification, and wherein similar reference characters designate corresponding parts throughout the several views,

Figure 1 is a perspective view of the body or filing portion of the receptacle, showing the relation of details for the filing of samples of fabric.

Figure 2 is a longitudinal cross sectional view taken through the cover of the receptacle, with the body portion in side elevation, and showing the latter having a large number of samples received therein.

Figure 3 is a transverse sectional view taken through the sample receptacle, showing a sample retained therein.

Figure 4 is a fragmentary longitudinal sectional view taken through one end of the receptacle body, showing the relation in which a sample may be received in frictionally held relation within a socket therein.

Figure 5 is a fragmentary plan view of an end portion of the receptacle, both ends being of the same construction.

Figure 6 is an edge elevation of the im-

proved sample for use in the improved receptacle.

In the drawing, wherein for the purpose of illustration is shown only a preferred embodiment of the invention, the letter A may generally designate the receptacle, which includes a box body or frame B, and a cover or closure C associable therewith; the body or frame B being adapted to receive the improved samples D in an efficiently filed and compact relation therein.

The body B of the box or receptacle is of elongated rectangular formation, including the side walls 10 and 11, and bottom wall 12, and end walls 13; all of these walls being preferably of cardboard and connected in the ordinary relation in which cardboard boxes are assembled. At the insides of each of the walls 10, 11, 12 and 13, thin flexible gluing strips 14 are placed, entirely longitudinally of said walls, from the bottom 12 to the top edges thereof, the same being adhered to said walls 10, 11 and 13, and presenting inner surfaces with an adhesive thereon to retain the spacing and partition strips and pieces to be subsequently described. At each end of the box, a dummy wall construction is built up of a plurality of strips of cardboard 18; the thickness of this dummy wall construction at each end wall 13 of the box, being determined by the lengths of the flaps of the samples D, and provided preferably in order to prevent the filing of a sample D adjacent either end of the box, so that the flexible flap thereof could be lapped over the exterior of the walls 13 and caught by the cover C when placing the latter thereon. These dummy end wall constructions made up of the cardboard strips 18 may be formed other than illustrated in the drawing, to a considerable thickness. Cardboard spacers 20 are placed in the box body B along each of the side walls 10 and 11 of the body B, in transverse right angled relation thereto, and alternating with the spacing strips 20 are the partition walls 21 of cardboard, the said partition walls 21 extending from side wall to side wall of the receptacle body B, and at the ends thereof being in engagement against the facing sides of the spacers 20; the latter thus being provided to space the partition walls 21 from each other to provide elongated pockets 24, which are preferably rectangular in height, and of the height of the body B from the bottom thereof to the top

edges of the side and end walls, 10, 11 and 13. The spacing members 20, in length transversely to the axis of the body B, may vary, but are preferably of the same dimension as the thickness of the dummy end walls formed by the strips 18, so that it is readily obvious that along each of the side walls 10 and 11, dummy side walls will be built up of a thickness substantially equivalent to the thickness of the dummy end walls formed by the strips 18, although this may vary; it being the purpose of the invention in providing the spacers 20, not only to space the partition walls 21 to provide the pockets 24, but also to prevent the placing of the samples so that the flaps might overlap the exterior of the side walls 10 and 11 and be caught by the cover and creased or disarranged upon the placement of the cover.

20 The partition walls 21 as well as the spacers 20 are held in a glued or adhered relation by an adhesive placed on the inside surface of the bottom wall 12, and on the inside surfaces of the strips 14 along the 25 inside surfaces of the side walls 10 and 11, as illustrated in the drawing.

30 The partition walls 21 are somewhat flexible longitudinally, although of preferably ordinary rigid cardboard, and the pockets 24 are quite narrow.

35 After the end and side dummy walls have been built up to the desired thicknesses, it being preferred that all of said dummy walls be of the same thickness, the tops of the same are covered by means of end strips 30 and 31, and the side covering strips 32 and 33, in an adhered glued relation to the top edges of the strips, spacers, and partitions 18, 20 and 21, in the relation of parts illustrated in Figure 1 of the drawing. This leaves exposed, on a plan view of the box body B, only the compartments or sockets 24 and the dividing partition walls 21 therebetween, as is illustrated in Figure 1 of the 45 drawing.

Referring to the improved sample device D, the same includes the flexible fabric or other sample portion 35, and the supporting holder 36. The sample portion 35, in case 50 the sample kit is to be used by hosiery manufacturers, is a section of hosiery taken transversely from a stocking. As the device is adaptable for use by ribbon manufacturers, or other fabric manufacturers, the 55 shape of the sample portion 35 may vary. For hosiery manufacturers, however, a section having been taken transversely from a stocking, it is of tubular form, and made flat and folded at 37, longitudinally thereof, and the ends are then brought together in 60 abutment, and placed in the upper portion of the socket or space 40 in the V-shaped cardboard frame 36, and clamped therein at 38, preferably by wire clamps of ordinary 65 construction. The V-shaped cardboard

frame 36 is of one piece construction, preferably being externally smooth and calendered, so that the same may readily slip into the socket 24. It is formed of a rectangular piece of material, bent along the 70 medial longitudinal line thereof into a V-shaped formation, and the end marginal portions of the fabric piece 35 secured only in the upper end of the space 40, so that the side walls of the V-shaped piece 36 are free to resiliently flex upon insertion into the socket 24, in order that they may have a frictional retention in the sockets 24 and will therefore not fall out freely from the 75 sockets if the box is accidentally inverted.

As to the fitting of the samples D in the sockets 24, the same is more particularly illustrated in Figures 1, 3 and 4 of the drawing. In length the holder portion 36 of the sample is less than the length of pockets 24, and it readily slips downwardly into any of the sockets 24; the depth of each socket 24 being sufficient only to accommodate the height of the holder 36, so that the flexible flap of fabric 35 extends exteriorly above the top surface of the box body B, and where the same may lay longitudinally of the box over the top edges of the partition walls 21, or over the top surfaces of other sample flaps, so that indicia 45 thereon may be visible, to observers, the same being pertinent to color, quality, or other characteristics of the particular fabric or material. It is to be noted from Figure 3 that the sides of the flaps of fabric cannot overlap the side walls 10 or 11 of the box body B. The ease with which the individual samples may be removed is illustrated in Figure 1, where the hand of the observer is shown pulling the sample from a socket, so that a prospective buyer may the more readily observe the characteristics of the fabric of the sample.

The closure C may be of a formation consistent with the number of samples which it is desired to retain in the box body B. If practically all of the sockets or sample receiving compartments 24 are filled, a closure C such as illustrated in the drawings is to be used, which consists of main outer side walls 50 and 51; end main walls 52; and a main top wall 53. Inserted at the inside of the walls 50, 51, 52 and 53 is a reinforcing and position determining insert, comprising side walls 55 and 56 arranged longitudinally at the insides of the walls 50 and 51, and adhered thereto in any approved glued or otherwise secured relation; the walls 55 and 56 being of less height than the walls 50 and 51, so that the free edges 56 thereof terminate at a distance from the edges 57 of the main side walls 51, this distance being equivalent to the height of the body walls 10 and 11. Similarly the insert of the cover has end walls 59 secured at the insides of the walls 52, the lower edges thereof bearing the 115 120 125 130

same spaced relation to the lower edges of the end walls 52 as above described for the side walls, and the insert also includes a top wall 60 secured in an adhering relation to the inside surface of the top wall 53. It is readily apparent that when the closure C is fitted on the body B, the latter is received in a frictional relation in the lower part of the closure C, with the top edges of the side and 10 end walls of the body B abutting the lower edges of the side and end insert walls 55, 56 and 59, as is illustrated in Figures 2 and 3 of the drawing. With this arrangement a space 65 is left in the box between the top 15 of the body B and the inside surface of the top wall construction of the closure C, wherein the flaps of the fabric samples may be received in an upstanding relation, if there are a large number of samples to be received 20 therein. If the body B is adapted to receive only a small number of samples, of course, the closure C may be lower than the illustration in Figures 2 and 3 of the drawing, to reduce the height of the space 65. 25 Practically all parts of the box construction are formed of economical material, such as cardboard, and the built up arrangement illustrated and described is the preferred form, although this may be modified to a 30 certain extent, if desired. The broad principle of the invention is the provision of an elongated box adapted to receive a plurality of efficiently filed and retained samples of fabric, or the like, in such relation that the 35 flaps thereof may be made individually visible, without detachment or disarrangement; the samples being so arranged that they may be easily detached, if desired. In the illustration is shown a box 12 inches long 40 by 4 inches wide, and in such type of box I have filed as many as seventy-seven samples, although this number may be varied as can quite readily be understood.

Various changes in the shape, size, and arrangement of parts may be made to the form of invention herein shown and described, without departing from the spirit of the same or the scope of the claims.

I claim:

1. A sample device comprising a box consisting of a body and a cover, the box body being of elongated formation including side walls and end walls and a bottom, with transverse closely spaced partition walls defining a plurality of compartments arranged longitudinally of the box, and samples detachably fitted into said compartments having relatively overlapping flexible portions arranged in stepped relation along the box on top of the partition walls.

2. In a sample kit the combination of a set of samples including holders and flexible flaps, and a body providing a plurality of sockets frictionally receiving the holders in a retained relation therein with the flaps

arranged exteriorly of the sockets in a loose relation over the top surfacing of said body.

3. In a sample kit the combination of an elongated narrow box body having a plurality of parallel elongated sockets arranged 70 with the lengths thereof transversely of the length of the box body, and the widths thereof longitudinally of the box body, and samples in said pockets each comprising a semi-rigid holder and a flexible sample portion, 75 the holders of the samples being inserted into the sockets so that the flexible sample portions are arranged exteriorly above the top surface of the box body.

4. In a sample kit the combination of an 80 elongated narrow box body having a plurality of parallel elongated sockets arranged with the lengths thereof transversely of the length of the box body and the widths thereof longitudinally of the box body and 85 samples in said pockets each comprising a semi-rigid holder and a flexible sample portion, the holders of the samples being inserted into the sockets so that the flexible sample portions are arranged exteriorly 90 above the top surface of the box body, and a cover for detachably receiving the box body to enclose the flexible portions therein.

5. In a sample box construction the combination of a box including a bottom, side walls, and end walls, built up dummy end and side walls at the inner sides of the end and side walls of the box body, and partition means arranged with the lengths thereof transverse to the dummy side walls in the 100 space between the latter to provide a plurality of pockets the lengths of each of which are arranged transversely to the dummy built up side walls.

6. In a sample box construction the combination of a box including a bottom, side walls, and end walls, built up dummy end and side walls at the inner sides of the end and side walls of the box body, partition means arranged with the lengths thereof transverse to the dummy side walls in the space between the latter to provide a plurality of pockets the lengths of each of which are arranged transversely to the dummy built up side walls, and a closure for detachably receiving the body therein having means 110 therein to space the top wall of the closure from the top surface of the body.

7. As an article of manufacture a sample device comprising a substantially V-shaped semi-rigid cardboard holder, and a sample piece having a marginal portion received in the upper end of the opening of the V-shaped holder and clamped therein so that the sample extends in a flap-like portion above the opening of the V-shaped holder.

8. In a sample kit the combination of a box body having elongated narrow open pockets therein, and sample devices in said pockets each comprising a transversely re- 120 125 130

silient holder and a flexible sample flap secured to the holder, the holders bearing such a relation to the pockets that when inserted therein the flaps will be extended exteriorly of the pocket.

9. In a sample kit the combination of an elongated narrow box body providing a plurality of narrow pockets arranged in parallel relation with the lengths thereof transversely of the length of the body, and samples in said pockets each providing a holder portion inserted into a pocket, and a flap portion extending exteriorly of the pocket, the pockets bearing such a relation to the holders that the sample flaps may overlap each other above the top of the box body and flap to one side or the other longitudinally of the box body.

10. In a sample kit the combination of an elongated narrow box body providing a plurality of narrow pockets arranged in parallel relation with the lengths thereof transversely of the length of the body, samples in said pockets each providing a holder portion inserted into a pocket, and a flap portion extending exteriorly of the pocket, the pockets bearing such a relation to the holders that the sample flaps may overlap each other above the top of the box body and flap to one side or the other longitudinally of the box body, and a closure for said box body receiving the box body therein to provide a space in the top of the closure for receiving the flaps in a non-engageable relation therein.

35 11. As an article of manufacture a sample device comprising a substantially V-shaped holder including spaced walls connected at similar edges thereof and spaced at the opposite edges, and a flexible sample secured

along the marginal portion thereof in the space at the free edges of the side walls of the holder with a flap of the sample extending from the holder, the side walls of the holder from the flexible sample portion therein to the connected edges of the holder being transversely resilient to flex under force and offer a resistance to said force.

45 12. In a sample device the combination of a substantially V-shaped holder providing spaced side walls with an opening at the free edges of said side walls, and a fabric sample portion of tubular formation flattened and folded along the axis thereof between the marginal edges, and having the free marginal portions thereof secured in the space between the free edges of the walls of the holder.

50 13. In a sample kit the combination of a box including a bottom, relatively thick side walls, relatively thick end walls, partitions in the box between the side and end walls arranged transversely to the side walls and in parallel relation to define narrow sockets, and sample devices including holders removably inserted into the sockets, each holder having connected therewith a movable sample portion adapted to overlie along the tops of the partitions.

55 14. In a sample box construction a box body having a compartment therein, and sample devices including holders disposed within the compartment, each of the holders having flaps movably connected with the holders foldable substantially flat along the top of the holders in a plane transverse with respect to said holders.

70 EDWIN MARSHALL KINSEY.
